ELECTRICAL METHOD AND MEANS FOR MINIMIZING CLOGGING OF A WATER WELL

SUMMARY THE INVENTION

This invention relates to a method and means for minimizing clogging in and around the inlet screen of a well made in unconsolidated earth or in and around the bore face of a well made in consolidated earth such as sandrock, where no screen is required. It concerns the positioning of at least one first electrode in the earth laterally outward of said inlet and positioning a second electrode at or inside said inlet. The first electrode is electrically connected to the negative terminal of a DC power source and the second electrode is connected to the positive terminal of the power source. A DC voltage is impressed across said first and second electrodes and creates an electrical current which through the earth from said inlet to said first electrode.

In the process of taking water from a water well there is a tendency for the inlet screen of the well or the face of the bore of a well in a consolidated earth aquifer to become clogged with particulate material deposited upon the inlet screen or bore face of the well and in the porous earth aquifer surrounding the well screen or well bore. It has been found that as the fluid is drawn from the surrounding subterranean earth towards the well inlet, electrical currents are naturally induced by the movement of the fluid in the earth materials. The amount of current induced has been found to be substantially proportionate to the rate of water flow and in the same direction. It is believed that the naturally induced currents cause a substantial amount of particulate mineral material to electro-chemically drop out of solution and to be deposited around the well inlet and upon the well screen or bore face causing the inlet to become so clogged that the capacity of the well is reduced. In this invention a controlled electrical current is introduced within the fluid bearing earth materials which opposes these naturally induced electrical currents and serves to reduce the amount of particulate material dropped out of solution and deposited around and upon the well screen or bore face.

It is therefore an object of this invention to provide a method and means for minimizing clogging of the inlet screen or bore face of a well by introducing within the earth around said well screen or bore face a controlled electrical current flowing away from the well inlet to substantially neutralize or reverse the natural earth currents and reduce the rate and amount of deposit of mineral material around and upon the screen or bore face.

It is another object of this invention to provide a method and apparatus for increasing the productive life of a well.

Other objects of this invention will become apparent upon a reading of the invention's description.

BRIEF DESCRIPTION OF THE DRAWING

The figure illustrated is a vertical view in section of one embodiment of this invention.

DESCRIPTION OF THE PREFERRED EMBODIMENT

The preferred embodiment illustrated is not intended to be exhaustive or to limit the invention to the precise form disclosed. It is chosen and described in order to best explain the principles of the invention and its application and practical use to thereby enable others skilled in the art to best utilize the invention.

The numeral 10 designates a substantially vertical tubular well casing having an upper end part 11 extending above ground and a lower end part 13 projecting into a porous fluid bearing subterranean earth stratum or aquifer 12. A reticulated well inlet screen 14 is connected to lower end part 13 of well casing 10. In cases of wells in consolidated earth, the well casing terminates within the consolidated earth and a bore is formed in the consolidated earth aquifer below and in communication with the well casing. A concrete or other suitable

foundation or pad 16 may enclose the upper end part 11 of well casing 10 to serve as a support for a well pump 18. Well pump 18 includes a housing 20 which is positioned over well casing 10 and is preferably mounted upon concrete pad 16. Housing 20 includes a pump outlet conduit 22. A motor 24 is mounted to the top of pump housing 20 and includes a vertical shaft 26 which extends downwardly through the pump housing into well casing 10. A plurality of impellers 28 are connected to the lower end of shaft 26 preferably below water level. A pump column pipe 21 is suspended from housing 20 and communicates with outlet 22. Pipe 21 extends vertically downwardly in well casing 10 and receives with clearance motor shaft 26 and includes an enlarged part or bowl 23 which houses pump impellers 28. Lower open end 26 of column pipe 21 preferably extends substantially below fluid level 29 in well casing 10 and terminates above the upper edge of well screen 14.

Pump motor 24 rotates shaft 26 and connected impellers 28. Fluid, such as water, is drawn by impellers 28 from earth stratum or aquifer 12 through well screen 14 and is forced upwardly through column pipe 21 into pump housing 20 and outlet conduit 22.

Electrode means encircle screen 14 within earth stratum 12.

Thus a plurality of electrodes 32 may be positioned in a circumferential set about well casing 10 and extend vertically in the earth. Electrodes 32 are substantially equally spaced and preferably are located at substantially equal radial distances from well casing 10. Each electrode 32 preferably includes an electrically conductive rod 31 and an insulative coating 33 and has an upper end which projects slightly above ground and a lower end which extends to the approximate depth of well screen 14. The insulative coating 33 at the lower end of each electrode 32 terminates at the approximate level of the upper part of screen 14 to expose the lower end of rod 31. Alternately a conductor ring (not shown) may be buried at comparatively shallow depth, such as 4 feet to 8 feet, encircling and spaced from 5 feet to 20 feet or more from the well casing and connected to a conductor extending to and above ground level.

An electrode 38 may be disposed within well screen 14 or the bore hole and preferably extends substantially the full length thereof. Electrode 38 may be positioned within screen 14 by suitable support members secured to the screen or it may be suspended from an insulated conductive wire 40 which has its lower end in electrical contact with the electrode and its upper end attached by an insulator or non-conductive member 42 which is carried by the pump housing 20. In this embodiment well casing 10 and pump screen 14 are preferably constructed from a non-conductive material, such as plastic or fiber glass. In the event the well screen is formed of electrically conductive material, the screen may constitute an electrode by electrical connection of conductor 40 thereto.

A DC power source 44, such as a DC battery or generator, is electrically connected to electrodes 32 and 38 at or above ground level. The negative terminal of power source 44 is connected to upper ends of electrodes 32 and the positive terminal of power source 44 is connected to wire 40 which is electrically connected to electrode 38. Pump 18 is preferably suitably grounded, such as by a wire 45 and a resistor 46 connecting the pump housing to the negative terminal of power source 44.

In operation, the DC power source 44 impresses a voltage across electrodes 32 and 38 and creates electrical currents flowing through the earth from electrode 38 to electrodes 32 as indicated by the broken line arrows in the drawing. These currents oppose the fluid induced currents, indicated by solid line arrows, traveling through the fluid-bearing soil stratum towards well screen 14 or bore face. By thus countering these induced currents, the amount of particulate mineral material deposited upon the screen or bore face and within the adjacent surrounding porous earth is substantially reduced. The spacing of the electrodes 32 from well casing 10 and the amount of voltage of DC power source 44 are interrelated.

The electrodes 32 are preferably positioned 5 feet to 100 feet or more from the well screen 14. While the amount of voltage of DC power source 44 will vary according to the character of the fluid pumped, the resistance of the fluid-bearing earth stratum and the pumping rate of the fluid, such voltage will preferably be within the range of 5 to 50 volts. This method affords anodic protection to the well and cathodic protection to the pump.

In the event either or both well casing 10 and well screen are formed of electrically conductive material, the positive terminal of power source 44 may be electrically connected thereto. In such embodiment, the separate inner electrode 38 is not needed.

It is to be understood that the use of an impeller pump in the described embodiment of this invention is for purposes of illustration only and that other types of pumps, such as a reciprocating pump, may be utilized with this invention. The invention may also be applied to flowing artesian wells where no pumping means is required.

We claim:

1. An apparatus for minimizing accumulation of particulate

mineral material at a water well inlet defined at least in part by an electrically conductive reticulated screen, comprising at least one electrode positioned in the ground laterally outwardly of said inlet, a DC power source having its negative terminal electrically connected to said electrode and its positive terminal electrically connected to said screen so as to impress a voltage across said screen and said electrode and create an outwardly directed electrical current flowing from said screen to said electrode.

10 2. A method for minimizing accumulation of mineral material at a water well inlet having a reticulated screen of conductive material and the aquifer surrounding said inlet comprising the steps of positioning at least one electrode in the earth adjacent to but laterally outwardly spaced from said inlet, electrically connecting the negative terminal of a DC power source to said electrode and the positive terminal of said DC power source to said screen, and activating said DC power source during use of said well to impress a voltage across said electrode and screen and to create an outwardly directed electric current flowing to said electrode.
